FIG. 3.

FIG. 2.

Inventor

John Morrison, Jr.

By his Attorney

Walton Harrison -

UNITED STATES PATENT OFFICE.

JOHN MORRISON, JR., OF GLENS FALLS, NEW YORK.

BRUSH.

1,408,763.

Specification of Letters Patent.

Patented Mar. 7, 1922.

Application filed December 18, 1920. Serial No. 431,541.

To all whom it may concern:

Be it known that I, JOHN MORRISON, Jr., a citizen of the United States, residing in Glens Falls, in the county of Warren and State of New York, have invented certain new and useful Improvements in Brushes, of which the following is a full, clear, and exact description.

My invention relates to brushes, and more particularly to brushes of various types used, mostly by hand, for polishing shoes, brushing clothes, grooming horses, removing crumbs from tables, brushing the nails, etc.

15 By my invention, I seek to accomplish a number of distinct objects, among which are the following:

I. To render the brush strong, light and durable.

20 II. To increase the ease and facility which with the brush may be manufactured.

III. To render the brush capable of withstanding the destructive effects of hot and cold water.

25 IV. To so construct the brush as to diminish its liability to split, swell, crack, or become water-logged.

V. To give the brush such form and construction as to prevent it from rattling or 30 chattering when placed in contact with other articles and subjected to shocks and jars.

VI. To give the brush such form and construction as to enable the bristle tufts to be 35 held firmly in position at all times and under all conditions.

VII. To give the brush such form and construction that in its manufacture there may be utilized a maximum of waste materials, and that certain materials may be used 40 in the form of relatively small pieces.

VIII. To improve generally the efficiency of the brush.

Reference is made to the accompanying 45 drawing forming a part of this specification, and in which like characters of reference indicate like parts throughout the several figures.

Fig. 1 is a perspective of my improved 50 brush, partly broken away.

Fig. 2 is a fragmentary plan of a number of sections made preferably though not necessarily of resilient material, such as cork, used in the construction of my brushes.

55 Fig. 3 is a fragmentary plan of a portion of the unfinished brush back, showing how

the bristle tufts are held under pressure by the sections.

Fig. 4 is a section on the line 4—4 of Fig. 3, looking in the direction indicated by the 60 arrow.

Generally speaking, the back of my brush is made up of a number of distinct sections. These are made preferably of cork or other resilient material, but if desired they may 65 be made of suitable woods of various kinds, or even of aluminum. The bristle tufts are held in position partly by glue or cement, and partly by pressure between the tufts and the sections.

70 A number of the sections are shown at 4, 5, 6, and are provided with shallow notches 7, 8, 9, 10, the curvature of each notch being such that the form of the notch is approximately semi-cylindrical if the sections are 75 made of metal or other rigid material, or may be rendered substantially semi-cylindrical by pressure of the tufts, as herein-after described, in the event of the sections being made of resilient material such as 80 cork. It being understood that I do not limit myself to the use of any specific material for the sections, I will for the sake of simplicity of description consider that the sections shown are made of cork. The 85 notches 7, 8, 9, 10 can be cut very rapidly and easily, and therefore cheaply, by feeding the sections across a table through which cutters or saws, properly shaped and proportioned for the purpose, protrude to a 90 sufficient distance.

The bristle tufts are shown at 11, and are each provided with a butt 12. These butts extend into holes 10^a, each hole being formed by a pair of the notches 7, 8, 9, 10, 95 and being substantially cylindrical in form in the completed brush.

The several sections in the finished brush are secured together by glue, cement or other appropriate adhesive.

100 A slab or plate 14, made of light and strong material, such as cork, is glued upon the top of the sections. If the work be done neatly and skillfully no seam is visible between the member 14 and the sections, or between the sections. I designate the member 14 as a cap plate.

In practice, the bristles are formed into the bristle tufts and these are held in a die. Cement, glue or other appropriate 110 adhesive is applied to the butts of the bristle tufts, which protrude from the die. The

adhesive becomes wholly or partially hardened, as desired, before the sections are brought into contact with the butts of the bristle tufts.

- 5 The glue, cement or other adhesive thus applied to the butts having reached a proper degree of hardness, the sections are placed in between the rows of bristle tufts, so that the butt of each bristle tuft fits into a pair 10 of the notches 7, 8, 9, 10. Pressure is then applied to the sections, so that each bristle tuft is forced into the notches, thus to a slight extent altering the shape thereof, as may be seen by comparing Figures 2 and 3. 15 Each notch thus acquires, under the passive pressure of the bristle butt, a substantially cylindrical form. This done and the abutting surfaces of the sections being held together by the adhesive as above described, 20 each bristle butt must remain at all times under pressure. It also follows that the material of each section is maintained constantly under compression at the points where the material is in contact with the 25 bristle butt.

Owing to the saving of time in cutting the notches instead of boring round holes, there is considerable economy in making the brush of the construction above described.

- 30 The capping plate 14 increases the mechanical strength of the brush back as a whole, and has a tendency to prevent the entrance of water into certain portions of the seams between the sections. The capping plate also improves the general appearance of the brush back.

My improved brush, made as above described, is exceedingly light and strong, and will stand considerable abuse. It may be 40 used in hot water and in cold water for long periods of time without swelling, cracking or becoming water-logged. I have found in practice that the glue in the seams retains its tenacity and is not readily dissolved out or softened by the action of the water, either cold or hot. A brush of this kind may stand months of rough usage without showing signs of deterioration. It does not split at the seams, and it resists the 45 entrance of water. The bristle tufts do not pull out of the brush back, and the individual bristles do not pull out of the butts of the bristle tufts.

If a brush of this kind be carried upon a 50 train, say in a suit-case, and there placed

in contact with other articles and subjected to shocks and jars, it can make no rattling noise. If dropped upon the floor, it merely bounces, and is not easily broken, chipped or otherwise injured.

I do not limit myself to the precise mechanism shown, as variations may be made therefrom without departing from my invention as defined in my claims.

I claim—

1. A brush comprising a number of sections made of resilient material and provided with notches, and a plurality of bristle tufts, each having a butt which extends partly into a notch of one section and partly into a notch of a different section, said sections being held together by an adhesive substance.

2. In a brush the combination of a number of separate sections each made of resilient material and provided with notches, the notches of one section being severally disposed adjacent the respective notches of a different section, tufts of bristles so arranged so that each tuft extends partly into a notch of one section and partly into a notch of a different section, said sections being held together under pressure, so that each bristle tuft, by its passive pressure against the adjacent sections, slightly distorts the adjacent material of said sections and thus slightly changes the form of said notches.

3. In a brush the combination of a number of sections each having the form of a flat bar and provided with notches, the notches of one section mating the notches of a different section, a plurality of bristle tufts each extending partly into a notch of one section and partly into a notch of a different section, and an adhesive for holding 90 said sections together.

4. In a brush the combination of a number of sections made of cork and provided with notches, the notches of one section mating the notches of a different section, said sections being held together by an adhesive, and a plurality of bristle tufts, each having a butt occupying a notch in one section and a notch in a different section, said notches being of such form that with said butts occupying said notches certain portions of the cork immediately adjacent said notches are compressed to an appreciable extent, so as to hold said butts under pressure.

JOHN MORRISON, JR.
